WILLIAM GABRIEL, OF DETROIT, MICHIGAN.

REINFORCED CONCRETE TRACK-TIE.

No. 908,765.

Specification of Letters Patent.

Patented Jan. 5, 1909.

Application filed October 25, 1907. Serial No. 399,165.

To all whom it may concern:

Be it known that I, WILLIAM GABRIEL, a citizen of the United States of America, residing at Detroit, in the county of Wayne 5 and State of Michigan, have invented certain new and useful Improvements in Reinforced Concrete Track-Ties, of which the following is a specification, reference being had therein to the accompanying drawings.

10 In railway track construction, the rails are usually secured on wooden ties which afford them a yielding, elastic support, or on metal or concrete ties or the like, which are unyielding and are liable to fracture and disintegration under the shocks and impacts of the traffic, and are more or less destructive to the rolling stock.

15 This invention relates to track ties of the so called reinforced concrete type, which 20 yieldingly support the rails and gives the same cushioning effect as do wooden ties.

The invention consists in the matters hereinafter set forth, and more particularly pointed out in the appended claims.

25 Referring to the drawings, Figure 1 is a view of a tie in perspective, partly broken away, which embodies features of the invention, with a portion of a rail thereon. Fig. 2 is a view in section on line $\alpha-\alpha$ of Fig. 1. 30 As shown in the drawings a substantially rectangular reinforcing frame having the general contour and dimensions of a standard tie preferably with inclined sides and ends, is formed of suitable metal rods or 35 strips.

In the preferred form of construction, a metal strip or rod is bent near its middle at right angles to form a double L, and is down-turned transversely to the plane thereof near 40 its body 2 to form corner posts 3. Its arms 4 are each reverted in a double L, the bodies of the bends forming posts 5 corresponding to the posts 3, and the end portions 6 of the lower reach 7 of the arms 4 being inbent 45 against the body 2. The frame is completed by a short bar 8 with inturned ends 9 lying between corners formed by the posts 5 and the lower reaches 7. The frame is then wound from end to end by a wire 10 in two 50 layers overlapping each other at regular intervals to form a diamond shaped mesh. Supplemental wing frames or brackets consisting of sheet metal plates 11 each bent to form a rounded corner 12 are secured to the main frame to broaden the tie top so that the 55 tie presents a rectangular section at the

points on which the rails rest, their ends 13 being hooked around the frame. A longitudinally disposed rod 14 is secured beneath the wire 10 and is bent on itself near each 60 end between the brackets 11 in flat S loops in whose bends 15 upright track bolts 16 are secured.

A hollow shell 17 open at each end of concrete or like cementitious material is molded 65 around the frame, the bracket portions being preferably solid, and the interior preferably being rectangular in section. The upper face of the shell at the bracket frames is transversely gained; the broad grooves 18 being crossed by track suspension wires 19 wound around the frame and brackets and embedded in the upper part of the concrete, the portions of the wire across the grooves being kept in proper parallel relation by a 70 spacing medium 20 allowing their limited vibration and movement under load, this medium being a mixture of tar and hair or like material which is yielding and tenacious and does not fracture. A pair of blocks or 75 struts 21 of the same material as the shell and of proper dimensions are each secured in place between the brackets under the bodies of the suspension wires by wooden wedges 22 driven above the block. Reinforcing members may be embedded in the 80 block if desired.

A thin sheet metal track plate 23 suitably apertured to receive the track bolts 16 is laid on the tie over the suspension wires, and 90 a track rail as 24 may be secured thereon by suitable washers and lock nuts 25 on the 95 bolts.

Longitudinal grooves 26 with broadly rounded bottoms are formed in the base of 95 the tie so that it may be readily slid under the rails or be removed therefrom and the ballast readily worked up under the tie as it is forced into place. Suitable drainage ducts 27 may be provided for the interior. 100

While the form of the tie body and the disposition of the reinforcements herein illustrated are preferable, as the body of the tie while light is rigid and its walls are not liable to fracture under the jarring and 105 pounding they receive, any construction which will attain these results may be used.

The chief feature of the invention is the resilient yielding shock absorbing support afforded the rails by the reinforcing wires 110 and the spacing medium with which they are surrounded. In case the wires are mo-

mentarily depressed until they touch the thin layer of concrete above the wooden wedge, as the yielding mass which surrounds them may admit of this, the wedge itself acts as a cushion to prevent the minor shocks and jars reaching the shell of concrete, thus providing a rigid body with a yielding support integrally formed thereon for each rail.

What I claim as my invention is:—

- 10 1. A track tie having a body of cementitious material, inserts of yielding material integral with the tie face, and rail suspension wires embedded in the body passing through the inserts.
- 15 2. A track tie consisting of a hollow body of cementitious material, inserts of yielding material in the face of the tie, rail suspension wires embedded in the body passing through the inserts and struts of cementitious material removably secured in the body beneath the inserts.
- 20 3. A track tie consisting of a hollow body of cementitious material, inserts of yielding material in the face of the tie, rail suspension wires embedded in the body passing through the inserts, struts of cementitious material removably secured in the body beneath the inserts, and a wedge of wood or similarly-elastic material between each strut and the insert.
- 25 4. A track tie having a body of cementitious material, inserts of yielding material integral with the tie face and rail suspension

wires embedded in the body passing through the inserts, a combined rail securing and reinforcing frame partially embedded in the body, a rail plate on the tie face engaging the frame and means for holding the frame in engagement with a track rail.

35 5. A track tie comprising a substantially rectangular hollow reinforcing metal main frame having inwardly inclined corner posts, wire wound transversely on the frame in a double layer forming diamond shaped meshes, pairs of bracket frames secured to the frame at track gage distance apart, a rod longitudinally disposed beneath the wire layers bent on itself in a flat S-loop between each pair of brackets, a hollow shell of cementitious material forming an embedding for the assembled frame, rod and wires, 40 inserts of yielding material in transverse gains in the shell between each pair of brackets, track suspension wires wound around the brackets and embedded in the shell passing through the gains and inserts, 45 rail plates on the tie over the inserts, track bolts each held in a bend of the rod loops and extended through an aperture in the tie plate, and rail clamping means on the bolts.

50 In testimony whereof I affix my signature in presence of two witnesses.

55 WILLIAM GABRIEL.
